UNITED STATES PATENT OFFICE.

JOHN S. BRENNAN, OF MILWAUKEE, WISCONSIN.

BURNER.

Specification of Letters Patent. Patented Aug. 1, 1922.

1,424,149.

Application filed July 13, 1920. Serial No. 395,851.

To all whom it may concern:

Be it known that I, JOHN S. BRENNAN, a citizen of the United States, and resident of Milwaukee, in the county of Milwaukee and 5 State of Wisconsin, have invented certain new and useful Improvements in Burners; and I do hereby declare that the following is a full, clear, and exact description thereof.

My invention refers to hydro-carbon 10 burners, known to the trade as the wickless type, wherein some form of non-combustible wick is used, such as asbestos or analogous material.

The primary object of my invention is 15 to provide a simple, economical and effective burner, associated with a wick, which structure, as a whole, will be durable, "fool-proof" and can be produced at the lowest maximum manufacturing cost, while at the 20 same time, it will function to insure uniform distribution of the fuel oil to and through the wick and will also prevent clogging with its consequent imperfect combustion, the wick element being an advance in 25 the art over that type, such as is disclosed in Patent No. 1327858 issued to me January 13th, 1920.

Specific objects of my invention are:

To provide a strip or ribbon wick, where- 30 in the flat wick is normally of greater length than the circular area of its associated burner cup or channel, to insure a lap joint at its meeting edges whereby an uninterrupted circular flame will result, which de- 35 sired feature is impractical, wherein a ribbon wick is used having a butt-ended joint. In such cases, it has been demonstrated that variation between the length of a ribbon wick and the circular burner cup will fre- 40 quently result in creating a gap in the joint or break in the flame. Furthermore, by the lap joint mentioned, the wick can be ignited at any point and the circular train of the flame from the point of ignition will quickly 45 complete the cycle.

To provide a burner cup for the wick, 50 wherein its flow channel is approximately equal in width to twice the thickness of the wick, whereby the lap joint of said wick is frictionally held in place by the opposite

side walls of the burner flow channel, and the remainder of the circular flow channel forms a free space for the travel of the fuel oil between the side surfaces of the wick and one or both side walls of the chan- 55 nel, which are spaced from the face or faces of the wick, due to the single thickness thereof at all points except at the lap joint.

To provide a metallic reinforcing means carried by the wick for sustaining the same 60 rigidly as to width and for supporting said wick above the bottom of the flow channel, into which it is nested, whereby a bottom edge and one or both sides of the wick are exposed to the flow of fuel oil, so as to insure 65 perfect capillary feed and also to prevent choking of the fuel oil supply duct.

To provide the metallic reinforcing strip with end feet projecting above upper and lower edges of the same, whereby the said 70 feet, when overlapped, will straddle the supply duct and prevent it from choking.

To provide a wick cup wherein the flow channel is horizontally disposed, whereby uniformity in dieing out the blank is as- 75 sured and the cost of manufacture mate- rially reduced, it being understood that train channels, when arranged to slant to- ward the fuel oil duct, causes complication in the die work. To also provide the inner 80 wall of the fuel channel with an upward and inward taper to thus widen the mouth of the wick receiving flow chamber, whereby the wick can be more readily slipped into position in assemblage, and at the same time 85 such incline wall will insure uniformity in drawing the metal blank, and thereafter in shedding the finished product from the die.

With the above and other minor objects in view, the invention consists in certain peculiari- 90 ties of construction and combination of parts, as are herein set forth with refer- ence to the accompanying illustrations and subsequently defined in claims:

In the drawings,

Figure 1 represents a sectional, eleva- 95 tional view of a burner cup and wick em- bodying the features of my invention, the section being indicated by line 1-1 of Fig- ure 2.

100

Figure 2 is a plan view of the same.

Figure 3 represents an enlarged fragmentary sectional view of the burner cup, having fitted therein the lapped ends of a wick embodying the features of my invention, and particularly illustrating the means for preventing choking of the oil supply duct.

Figure 4 is a face view of a section embodying the features of my invention, the same being shown flattened out to more clearly illustrate its details of construction, and

Figure 5 is a cross sectional elevation of a modified form of wick receiving cup, fitted with a section embodying the broad principles of my invention, and in this form of cup, the wick is suspended from the horizontal bottom to the flow channel by indentures, it being understood that the flow channel is of approximately twice the width as the thickness of the wick.

Referring by character to the drawings, 1 represents a circular wick cup, the walls of the same being folded upon themselves to form a flow channel 2 at the point of fold, which flow channel is horizontally disposed and is of a width approximately equal to twice the thickness of a wick A, which is fitted therein, the same being hereinafter more fully described. The outer wall 3 of the wick cavity is shown vertically disposed and the inner wall 4 thereof in practice tapered upwardly and inwardly, so as to develop a V-shaped chamber having somewhat wider mouth for receiving the wick, in comparison to the width of the flow channel walls. The inner tapered walls 4 of the cup are merged into a vented flat cap piece 5 of the ordinary type.

Referring especially to Figures 3 and 4 of the drawings, the wick is of the ribbon type, that is, it is woven into strips and supplied in predetermined lengths, the same being of asbestos and preferably similar to that described in my patent referred to herein. The metallic strip 6 is affixed to the ribbon wick and secured at intermediate points by burrs 7, and the ends of the metal strips are folded over the end edges of the wick and formed with transversely projecting feet 8, which terminate above and below the burning edges of the wick as shown, it being understood that the same is reversible. The intermediate central portion of the strip is formed with transversely disposed feet 9, which correspond in height to the end feet 8.

Attention is directed to the fact that the length of the ribbon wick is greater than the length of the circular wick cavity of the cup, and hence, when said wick with its reinforcing strip 2 is shaped into circular form to fit the wick cavity, its ends are over-

lapped more or less as shown in Figure 2 of 65 the drawings, whereby a double thickness at the point of lap is effected.

In lapping the wick into the cup cavity, I preferably position the overlapped joint, over the fuel oil supply duct 2', as indicated in Figures 1, 2 and 3. Hence, the legs 8 will straddle the fuel oil supply duct 2' and prevent clogging at this point particularly as the bottom edge of the wick fabric is held above the bottoms of the flow channel. 75 It will also be observed that owing to the fold about the end edges of the wick, the legs 8 are U-shaped in cross section, so as to add rigidity to the structure, and in order to add this same rigidity to the intermediate legs 9, their ends are folded upon themselves to form a double thickness as best shown in Figure 1. As clearly defined in Figures 1 and 5 of the drawings, when the wick is inserted in position, it will be noted that the flow cavity space from wall to wall is of approximately the same width as the combined thickness of the lapped ends of the wick, and hence, the wick at this point is frictionally held so as to maintain its 90 position with relation to the flow channel and associated parts of the cup.

It will be further noted that the remainder of the wick which surrounds the inner wall 4 is spaced both from said inner wall 95 and from the outer wall, whereby a free passage to permit the flow of oil about the lower edge of the wick is attained, it being understood that in this exemplification of the invention the wick is held from the outer wall 3 by the thickness of the metallic reinforcing strip 6. Hence, a greater unobstructed passage of flow channel is had, due to the spaced relations of the wick and channel walls, and the lower end of said 105 wick is, as seen, held a slight distance from the bottom of the flow channel by the legs 8 and 9.

As shown in Figure 5, the lower edge of the wick in some instances may be held in 110 suspension above the bottom of the flow channel 2 by indentures 8' and 9' respectively, which are formed by pressing or indenting the walls of said channel at predetermined height about the circumference of 116 it.

I claim:

1. The combination of a ribbon wick adapted to be folded into circular shape, a reinforcing metallic strip having a plurality of legs extending therefrom to a point beyond the wick edges and spaced apart along the circumference, and a circular wick cup for the reception of the strip, the legs of said wick being adapted to rest upon 120 the bottom of the cup for holding the wick edge in suspension and permitting fuel to reach said edge and the sides of the wick.

2. The combination of a ribbon wick adapted to be folded in circular shape and having its ends lapped to form a double thickness at one point, a cup therefor having a flow chamber including a horizontally disposed bottom and a vertically tapered inner wall, the base of which chamber is of a width equal to the thickness of the wick at its lapped ends, and means carried by and extending below the wick for supporting the bottom edge of the same at a predetermined height from the bottom of the flow chamber.

In testimony that I claim the foregoing I have hereunto set my hand at Milwaukee, in the county of Milwaukee, and State of Wisconsin.

JOHN S. BRENNAN.
